UNITED STATES PATENT OFFICE.

SEYMOUR W. PEREGRINE, OF GRAND RAPIDS, MICHIGAN.

PAINTING-MACHINE.

SPECIFICATION forming part of Letters Patent No. 425,547, dated April 15, 1890.

Application filed March 1, 1889. Serial No. 301,659. (No model.)

To all whom it may concern:

Be it known that I, SEYMOUR W. PEREGRINE, of Grand Rapids, in the county of Kent and State of Michigan, have invented 5 a new and useful Improvement in Painting-Machines; and I do hereby declare that the following is a full, clear, and exact description of the same.

The object of my invention is to produce 10 an apparatus for staining the ends of slats composing the backs and seats of school-seats. It being desirable to provide a machine capable of adjustment, whereby alternate slats may be painted or stained to suit 15 different widths of slats, I employ a series of laterally-adjustable pads, surfaces, or brushes, which may be fixed in position in line with the slats desired to be painted after the manner shown in my application filed April 10, 20 1888, No. 270,214.

My invention consists of a table for supporting the school seat or back and a series 25 of staining surfaces, brushes, or pads arranged in direct line with the edge of said seat or back, whereby the edges or ends of the slats will be stained when the seat and staining devices are made to abut against each other.

It consists, further, of a table for receiving 30 the seat or back, a series of staining devices arranged in line with the edge of said seat or back, and a guide against which the seat or back abuts to accurately determine its position in relation to the staining devices.

It consists, further, of a series of pads on 35 movable supports and a tank, the said supports being arranged to immerse the pads in the staining material when moved.

It consists, also, of a movable support for 40 the staining devices combined with means for operating said support to and from the slat, whereby the slat ends and staining devices are caused to abut.

It consists, further, of a table, of a series of 45 movable supports, each support carrying one or more staining devices, which may be brought into line with the ends of the slats by movement of said movable supports, and as said pads may vary in size and configuration to suit different sizes and shapes of slats—that 50 is, their cross-section configuration—the machine is rendered capable by adjustment of

staining seats or backs in which the slats vary in size or shape.

The special form of pad, the details of construction, and the means of adjustment 55 also form part of my invention.

In the drawings, Figure 1 is a side view of the table with the staining devices supported thereby and the seat ready to be moved against them, showing also one manner of 60 arranging the tank. Fig. 2 is a detail perspective view of one end of the table with the staining devices, showing the construction which enables the table to be adjusted for different lengths. Fig. 3 is a detail view 65 of a portion of the table with a modified arrangement of table and staining devices, illustrating also different means by which the machine may be adapted to different lengths of seats and backs, and means for moving 70 the pads against the seat. Fig. 4 is a modified form of staining device adapted more especially to slats which are not connected by tongues and grooves, or, in other words, which have plain edges. Fig. 5 is a detail 75 view of a modification.

In the drawings, *e'* represents the supporting-table, having a set of staining devices *B' B'* at each end thereof. The seat *C* is placed upon the table between the two sets of staining devices, and by moving it first one way and then the other the end edges of the seat are forced against the staining devices and the ends of the slats stained according to position of the staining devices in relation to 85 said slats, which, as in Fig. 1, will stain each alternate slat. The table is made in two parts, which parts are connected by slotted bars *1 2* and suitable holding-screws, which connection allows the table ends to be adjusted and fixed 90 in position at greater or less distances apart, to suit different lengths of seats or backs.

The staining devices, preferably pads *A*, are carried upon movable supports, which, as shown, consist of cylinders or drums *c*, and 95 these in turn are carried by shafts *e*, journaled in the bearings on the table *e'*. When the slats to be stained are connected by tongues and grooves, the pads are of corresponding shape, those for the outside slats being plain on one 100 edge and having a projection or notch on the other end to correspond with the tongue or

groove of the slat, and those for the inside slats being formed with a notch on one side to correspond with the groove of the slat and a projection on the other side to correspond 5 with the tongue, as at a' . The shafts upon which the movable supports are fixed extend transversely of the table, and openings are formed in the table beneath the supports to permit their partial movement and also permit 10 the tanks which hold the staining material to be properly positioned in relation to said supports.

The preferred arrangement of tanks is shown in Fig. 1, located in the openings in 15 the table beneath the movable supports, so that as the shafts are turned the staining-pads would be caused to pass into the staining material and be made ready to act upon any slats of the school-seats. The staining-pads, 20 as before stated, are positioned upon their several supports substantially in line with each other, and where the seat is curved they are arranged in corresponding manner to be in line with the slats desired to be painted, 25 so that as the seat is moved forward it strikes fairly against the pads, and by reason of the shape and size of said pads corresponding exactly to the ends of the slats the stain will be applied only to the desired slats, without 30 touching upon those adjacent thereto. The movable supports are splined to the shafts, so as to have lateral movement, and are provided with grooved bosses on one side, as at 5, which receive the forked ends of the levers 6, held 35 in the brackets 8. By means of these levers the supports may be adjusted laterally to bring the pads into line with any desired slats. The seat is guided in its movement along the 40 table to the pads by means of an adjustable strip 10, fixed to the table.

The shaft is turned by means of a treadle and strap $e^2 f$, the latter of which passes about the pulley g on the end of the shaft. For returning the shaft after it has been moved in 45 one direction, I provide a spiral spring v , secured to the bracket and to one of the movable supports. The rotary movement of the movable supports is limited, so that the pads will stand in line with the edge of the seat, 50 and this stoppage of the movement is secured by means of an adjustable stop x , which arrests the movable supports as the spring draws them back and raises the pads from the staining material. For securing accuracy 55 in guiding the seat and in making the pads register exactly with the slats, I employ arms n , supported on the shaft and extending through slots in the several drums directly above the staining-pads. These arms are adjustable and can be fastened in position by 60 means of set-screws extending through slots in the sides of the drums.

In operating the apparatus the attendant places the back or seat upon the table with 65 one edge against the guide, and by a movement of the treadle the pads are immersed, the tank of course being large enough to al-

low the guide-arms n movement therein. The pressure upon the treadle being relieved, the spring rotates the drums in the opposite direction until contact is made with the adjustable stop, at which time the movement will be arrested and the pads be in line with the slat ends, and then by moving the seat or back along the table its edge will pass beneath the guide-arms n , which will insure the accurate guidance and registering of the slat ends with the pads. The adjustable stop-arm rests upon a spring-cushion y , and thus when the seat and pads are made to abut and the arms n bear upon the seat the said spring-cushion exerts a slight yielding pressure to hold the arms firmly in place. When it is desired to bring another set of staining devices into action, it is necessary to adjust the 85 operating strap and spring. The arms extend forward and have upturned ends adapted to bear upon the surface of the seat, and thus determine more accurately the position at which the pads stand in line with the end of 90 the slat.

In Fig. 3 I show a modified arrangement of tank and pad. In this case the pad is held by a supplemental tank or pot D , which is secured to a drum E or similar movable support carried by the shaft e . Several series of these supplemental tanks or pots carrying staining-brushes may be employed, as at $x' y'$, Fig. 3, to suit the slats of different shapes and sizes. Each staining-pot is provided with 100 a nipple adapted to receive a tube i , extending from a main stain-tank F , supported above the table in a suitable position. The tubes are provided with suitable cut-off valves, and when these are open the staining material passes from the main tank into the supplemental tank or pot and is absorbed 105 by the staining pads or brushes, which are then ready to receive the thrust of the school seat or back. Arms h' are used in this modification, as in that previously described, to make the pad register with the slat ends. The drums may be turned and fixed in position to bring any series of staining-pads of different sizes and shape into alignment with the slats, 115 in which case, of course, the tubes must be changed from one set of devices to the other. The table is formed with an opening to receive the movable supports. The supporting-shaft is journaled in boxes 12 at the rear ends of 120 the sliding plate 13. This plate slides in ways formed in the table, and has screws by which it may be fixed in a position to locate the two sets of staining devices at the table ends any 125 desired distance apart to suit different lengths of slats. In this figure, also, I illustrate means by which the staining devices may be moved against and away from the seat, which may be held stationary, and this method of operation is preferred by me to that previously described, in which the seat is moved against 130 the staining-pads. This means consists of the lever 14, rock-shaft 15, the arm 16, and the rod 17, connected to the plate 13. By

moving the lever the shaft is rocked and the plate 13 moved to thrust the pads against the seat, the screws moving in the ways and allowing this action. The tubes *i* are of course made sufficiently long to permit this movement. I do not confine the application of these means to the particular arrangement illustrated in Fig. 3, it being shown in that construction merely for convenience, as it is obvious that the shaft shown in Fig. 1 may be mounted in a sliding plate, as 13, having connection to an operating-lever. It will be understood, also, that the means shown in Fig. 1 for adjusting the devices toward and from each other, consisting of the slotted bars 1 2, are intended for use with the arrangement shown in Fig. 3.

In Fig. 5 is shown a modification, in which supporting-arms, as *M*, are employed, instead of the rollers, and in this instance the pads are removably held by a set-screw *x*², which, when loosened, allows the pad to be withdrawn and a fresh one of different shape and size inserted.

In Fig. 4 I have shown means for staining the slats especially adapted to a seat composed of slats having plain edges or without any tongues or grooves. These consist simply of a belt of width equal to the width of the slat to be painted, a pair of rollers for supporting said belt in a vertical position or across the line of movement of the seat, and of a suitable staining-tank in which one of the rollers is located, in order that the staining material will be applied to the belt.

I claim as my invention—

1. A machine for staining or painting the ends of school seats or backs, consisting of a table and a staining device with a staining-surface conforming in shape to the seat edge, arranged across said table in direct line with the seat end, and having its staining-face approximately at right angles to the seat end and extending entirely across the same, where-by the seat and staining device abut squarely against each other and effect the staining of the seat end by said contact, substantially as described.

2. A machine for staining or painting the ends of slats of school seats or backs, consisting of a table, a series of staining devices arranged across the table at one point, each device of the series being in direct line with the slat end desired to be painted, the staining-face of said device being in position to extend entirely across the slat end when in contact therewith, substantially as described.

3. In combination, a table adapted to receive the seat or back, a series of staining devices arranged across said table and in line

with said slat ends, whereby they may be brought in contact therewith, and a guide on the table, substantially as described.

4. In combination, the table, the tank, the staining devices arranged across said table and in line with the slats of the seats or backs, presenting surfaces to bear upon the entire end of the desired slats, the said staining devices being carried on supports having movement across the plane of the table, substantially as described.

5. In combination with the table, a shaft, a longitudinally-adjustable support thereon, and independent staining devices on said support, substantially as described.

6. In combination, the table, the series of staining devices arranged across the same, and having staining-surfaces approximately at right angles to the slat ends and extending across the same, the said devices being on a movable support, whereby the slats are stained by forcing the series of staining-surfaces into contact with the slat ends, substantially as described.

7. In combination, the table, the staining devices carried by movable supports on said table, and the arms *n*, projecting forward from said supports beyond the staining-pads, adapted to bear on the school seat or back to guide the parts accurately as they are moved together, substantially as described.

8. In combination, the table, the staining-pad, the movable supports therefor having movement across the plane of the table, and a stop for limiting the movement of said supports, substantially as described.

9. In combination, the table, the staining devices, the movable supports therefor, the arms *n*, the stop-arm, and the spring-cushion, all arranged and operating substantially as described.

10. In combination, a table, a set of staining devices at or near each end thereof arranged at right angles across the table to make contact with the slat ends located between them, said devices being adjustable, substantially as described.

11. In combination, a supporting-table, a series of staining devices arranged across said table and in line with the slat ends of the school-seats, said staining devices having notches and projections on their sides, substantially as described.

In testimony whereof I have signed my name to this specification in the presence of two subscribing witnesses.

SEYMOUR W. PEREGRINE.
